UNITED STATES PATENT OFFICE.

HUGH LINLEY BYRD, OF STOCKPORT, ENGLAND, ASSIGNOR TO DREY, SIMPSON & COMPANY, LIMITED, OF SOUTH REDDISH, NEAR STOCKPORT, ENGLAND.

MEANS FOR TENSIONING YARNS OR THE LIKE IN LOOMS, WINDING, DOUBLING, AND OTHER TEXTILE MACHINES.

Application filed March 31, 1927, Serial No. 179,917, and in Great Britain April 6, 1926.

This invention has reference to means for tensioning yarns or the like in looms, winding, doubling and other textile machines in which the rate of travel of the yarn or the like is subject to variation, and it has for its object to provide improved means for taking up slack which may occur in the yarn or the like at certain places or times due to over-running of the supply or the 10 pull on the yarn or the like temporarily or momentarily decreasing or ceasing.

A means for the purpose referred to, according to this invention, comprises a roller and a pressure member or members between 15 which the yarn or the like passes and is lightly gripped, said roller being positively driven in the opposite direction to the travel of the yarn or the like so that it tends to travel the yarn or the like backwards and 20 impart a slight retarding effect upon same. By these means the yarn or the like is kept always taut beyond the roller, and slack which may occur is at once taken up by the roller travelling the yarn or the like backwards.

In the accompanying drawings Figs. 1 and 2 are elevations at right angles to each other illustrating one embodiment of the invention, and Fig. 3 is an elevation illustrating a modification thereof. Figs. 4 and 30 5 are elevations at right angles to each other of another embodiment of the invention, and Fig. 6 is a plan of Fig. 5.

Referring to the drawing, the embodiment 35 of the invention illustrated in Figs. 1 and 2 comprises a pair of rollers 7, 8. The yarn 9 is drawn off from a cheese 10 through a guide 11 and passes between the rollers 7, 8 to a guide 12 whence it passes as required. The lower roller 7 is positively driven by a 40 belt 13 engaging in a groove 14, or any other suitable means from an appropriate rotating part of the machine, in a direction opposite to that of the travel of the yarn. The upper roller 8 is of light construction 45 and bears lightly upon the yarn. This latter is achieved by making the roller 7 of two diameters 7^a, 7^b so as to provide between the part of lesser diameter and the upper roller 8 a space slightly less than the thickness of the yarn 9 which lies therein.

The rollers 7 and 8 are carried in a bracket 50 15, the upper roller 8 being mounted in slotted bearings 16 in which it is free to

move vertically to adapt itself to inequalities in the thickness of the yarn 9. The surfaces of the rollers may, if desired, be covered with felt or any other suitable material.

Normally the yarn 9 is drawn freely between the rollers 7, 8 in the direction indicated by the arrows. When, however, the travel of the yarn is interrupted, any slack which may occur therein at the right side of the rollers 7, 8 as shown in Fig. 1, is at once taken out and the yarn maintained taut at such side of the rollers, by the latter travelling the yarn backwards, i. e., towards the cheese 10.

In some cases the upper pressure roller 8 may co-act with two positively driven lower rollers 7 as shown in Fig. 3, or, if desired, the yarn may pass between and be controlled by two or more sets of lower and upper rollers.

In the embodiment of the invention illustrated in Figs. 4, 5 and 6, the lower roller 7 is provided with a grooved periphery in which the yarn lies, and the upper roller 8 aforesaid is replaced by one or more balls 17 arranged in holders 18, from the lower ends of which they project to bear on the yarn lying in the groove of the roller. The holders 18 preferably consist of short tubes mounted in spring clips carried by the bracket 15 and have their lower ends gapped as at 19 to permit the free passage of the yarn 9.

In this embodiment of the invention, as before, any slack which may occur at the delivery side of the roller 7 is taken up by the roller 7, acting in conjunction with the balls 17, travelling the yarn backwards. Balls 17 of different weight may be mounted in the holders 18 according to the tension it is desired to maintain on the yarn and two or more sets of rollers and balls may be employed.

The invention is especially applicable for use in shuttleless looms in which weft drawn from a supply at one side or both sides of the loom is inserted into the warp shed by needle-like or other inserting devices. In such application of the invention it serves to take up the slack which occurs in the weft during the return of the reed and slay after beating up the picking position and so maintains the weft taut to ensure its subsequent

engagement by the inserting device at the next pick. The slack referred to is taken up by reason of the yarn being caused to travel in a reverse direction by the action of 5 the rollers of the tensioning means. The invention is, however, also applicable for use in other textile machines in which the travel of the yarn or the like is subject to variations.

10 What I claim as my invention and desire to secure by Letters Patent is:—

1. The improved means for tensioning yarns in looms, winding, doubling and other textile machines, comprising a roller and a 15 pressure member or members between which the yarn passes and is lightly gripped, said roller being positively driven in a direction opposite to the travel of the yarn so that it tends to travel the yarn backwards, and so

travels the yarn when slack occurs therein, 20 substantially as set forth.

2. Tensioning means for yarn, according to claim 1, comprising the combination with the positively driven roller, of a pressure roller co-acting therewith and between 25 which and the driven roller the yarn passes and is lightly gripped, substantially as set forth.

3. Tensioning means for yarn comprising in combination, a positively driven roller 30 and a pressure roller coacting therewith, one of said rollers having a portion of reduced diameter to provide between the rollers a space slightly less than the thickness of the yarn in which to receive the yarn. 35

In witness whereof I have hereunto set my hand.

HUGH LINLEY BYRD.
